UNITED STATES PATENT OFFICE.

BARNEY C. WICKERS, OF LEBANON, INDIANA.

SHOEHORN.

Application filed February 10, 1928. Serial No. 253,462.

This invention relates to a combined shoe horn and jack, the primary object of the invention being to provide a device of this character having a substantially long handle so that a person using the device may remove or position a shoe without the necessity of stooping.

An important object of the invention is to provide a device of this character including lateral flanges formed of resilient metal so that the flanges will grip the heel portion of a rubber overshoe, or shoe to the end that downward pressure on the handle of the device will result in the overshoe or shoe being removed.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a front elevational view of a combined shoe horn and shoe jack, constructed in accordance with the invention.

Figure 2 is a side elevational view thereof, a portion of the handle being shown in section.

Figure 3 is a side elevational view of the device showing the application of the device as a shoe jack.

Referring to the drawing in detail, the device includes an elongated body portion indicated generally by the reference character 5, the same being constructed of resilient sheet metal.

As shown, the side edges of the body portion are curved upwardly to define a shoe horn 6, the lower corners thereof being cut away as at 7 so that the device may be readily positioned in a shoe.

The upper extremity of the body portion curves rearwardly as at 8 where it is supplied with openings to receive the bolts 9 that also pass through openings in the handle 10 and secure the body portion to the handle 10. It is of course understood that the handle 10

is substantially long, so that the device may be used either as a shoe horn or shoe jack, without the necessity of the person using the device, stooping over as is the usual case when putting on rubber overshoes.

Formed integral with the side edges of the body portion are substantially wide flanges 11, which are also curved outwardly, the flanges 11 having outwardly curved upper portions 12 designed to guide the shoe or foot of the person when applying the shoe to the foot.

As shown by the drawing, the lower edges of the flanges 11 terminate in spaced relation with the lower end of the body portion 5 with the result that the device may be efficiently used as a shoe horn for applying a shoe or rubber.

It will also be seen that owing to the shape of the upper ends 12 of the flanges 11, a person's foot will be guided between the flanges 11 and the shoe or rubber being positioned will be held in its proper position with respect to the shoe or foot of the wearer.

As shown by Figure 3, the device is used as a jack for removing a rubber, in which case the device is forced downwardly over the heel of the rubber, and when positioned may be given a further push by the operator to force the rubber from the shoe.

The device may also be used as a jack by merely inserting the heel of the shoe or rubber between the flanges 11 which being of resilient metal, grip the heel and hold it while the shoe or rubber is being removed.

I claim:

In a device of the character described, a body portion including a length of sheet metal having its side edges curved upwardly, flanges extending outwardly from the curved side edges of the body portion, the lower ends of the flanges extending inwardly to grip an overshoe to force the overshoe from its position on a shoe, the lower ends of the flanges being spaced from the lower end of the body portion to define a shoe horn, and the upper ends of the flanges being curved outwardly to define a guide.

In testimony that I claim the foregoing as my own, I have hereto affixed my signature.

BARNEY C. WICKERS.
